UNITED STATES PATENT OFFICE

145,863

DESIGN FOR A CIGARETTE SERVER

Fred Zimbalist, Cleveland Heights, Ohio

Application December 22, 1945, Serial No. 125,018

Term of patent 7 years

(Cl. D85—2)

To all whom it may concern:

Be it known that I, Fred Zimbalist, a citizen of the United States and a resident of Cleveland Heights, Cuyahoga County, Ohio, have invented a new, original, and ornamental Design for a Cigarette Server, of which the following is a specification reference being had to the accompanying drawing, forming a part thereof.

In the drawing:

I claim:

The ornamental design for a cigarette server, substantially as shown.

FRED ZIMBALIST.
